UNITED STATES PATENT OFFICE.

EVERETT CODY, OF WASHINGTON, DISTRICT OF COLUMBIA.

DESIGN FOR A PENDANT.

61,032.

Specification for Design.

Patented June 6, 1922.

Application filed December 30, 1921. Serial No. 526,064. Term of patent 14 years.

To all whom it may concern:

Be it known that I, EVERETT CODY, a citizen of the United States of America, residing in Washington, in the District of Columbia, have invented a new, original, and ornamental Design for a Pendant, of which the following is a specification, reference being had to the accompanying drawing, forming part thereof.

In the drawing:

Fig. 2 is an edge elevation of the same.

I claim:

The ornamental design for a pendant, as shown.

EVERETT CODY.
